UNITED STATES PATENT OFFICE.

MARTIN H. BRIESEMEISTER, OF SOUTH MILWAUKEE, WISCONSIN.

DICEBOX.

Application filed May 31, 1927. Serial No. 195,415.

My invention refers to dice boxes and it has for its object to provide a simple, durable and sanitary dice box, the same being noiseless and constructed and arranged 5 in such manner that replacement of parts can readily be effected.

The specific object of my invention is to provide a box having a lining of soft yieldable material encased in a hard shell preferably composed of celluloid whereby the box at all times is rendered sanitary. The dice boxes are usually made of material which is porous and soft and which will readily absorb moisture of foreign matter 10 from the hands of the player whereby the boxes are rendered unsanitary. My invention by the use of a nonporous jacket will not thus absorb the unsanitary matters usually incurred by uses of dice boxes of the 15 standard types.

With the above and other minor objects in view, the invention consists in certain peculiarities of construction and combination of parts to be hereinafter fully set forth 20 with reference to the accompanying drawings and subsequently claimed.

In the drawings:

Figure 1 represents an elevation of a dice box embodying the features of my invention;

Figure 2 is a sectional elevation of the same;

Figure 3 is a side elevation of a detachable bottom section of the box assembly.

Referring by characters to the drawings, 35 1 represents a tubular section, preferably of rubber, which section constitutes an inner lining for the box.

The tubular inner lining is encased by a 40 shell 2, which is preferably composed of celluloid. Obviously, this shell will be in some case composed of metal or other suitable non-porous material which can be readily cleansed. The lower end of the shell 2 is inturned to form a flange 3.

The bottom of the dice box is formed 45 from a single disk-like unit 4, the said bottom being preferably composed of rubber. The bottom, as is best shown in Figure 3, is formed with an angular groove 5, and the

base line of the bottom is slightly curved to present a convex surface α forming a rocking support for the box.

Attention is directed to the fact that the bottom disk is of sufficient weight to overbalance the lighter upper portion of the box whereby said box, as a whole, will maintain its perpendicular position when it is supported upon a table or the like.

By forming the rubber disk bottom separate from the lining it will be observed that said disk bottom can readily be removed and replaced, it being understood that when it is assembled with reference to the shell 2, the said disk is compressed and inserted 65 in such manner that the groove 5 will engage the inturned flange 3 of the shell.

Thus it will be seen that the dice box as a whole is composed of 3 units, all of which can readily be assembled and separated in 70 the event that the box is to be cleaned or sterilized.

From the foregoing description it will be seen that a strictly sanitary dice box is provided, which can be thoroughly and quickly 75 cleaned by wiping off the outer surface of the shell, and furthermore when the box is in use the cushion lining and bottom will prevent noisy handling of the dice.

I claim:

1. A dice box comprising a non-porous continuous, rigid, outer shell and an inturned bottom flange, a removable rubber bottom of pliable material having an angular groove for engagement with the shell 85 flange, and a tubular lining fitting into the shell, the lining and bottom forming a noiseless surface for contact with dice.

2. A dice box comprising a continuous, rigid, outer shell having an inturned bottom flange, a rubber bottom having a cylindrical portion provided with a continuous groove within which said flange fits and having a rounded bottom projecting outwardly.

In testimony that I claim the foregoing I have hereunto set my hand at Milwaukee, in the county of Milwaukee and State of Wisconsin.

MARTIN H. BRIESEMEISTER.
